UNITED STATES PATENT OFFICE.

THOMAS J. KERWIN, OF CHICAGO, ILLINOIS, ASSIGNOR TO EDMUND & JONES CORPORATION, A CORPORATION OF NEW YORK.

VEHICLE LAMP.

Application filed September 16, 1922. Serial No. 588,578.

To all whom it may concern:

Be it known that I, THOMAS J. KERWIN, citizen of the United States, residing at Chicago, in the county of Cook and State of Illinois, have invented certain new and useful Improvements in a Vehicle Lamp; and I do hereby declare the following to be a full, clear, and exact description of the invention, such as will enable others skilled in the art to which it appertains to make and use the same.

My invention relates to illuminating appliances and in some of its general aspects aims to provide a lamp casing, lamp-socket and supporting bracket assembly in which certain portions jointly secure the said three main constituent parts to each other, and in which a portion of the lamp casing also serves as a wall for resisting a spring forming an operative portion of the socket.

Viewed in one of its more particular aspects, my invention aims to provide a lamp casing and socket assembly in which a shell portion of the socket is formed for clamping the socket to the lamp casing and desirably also for clamping both of the said members to a supporting bracket. Moreover, my invention aims to provide a simple-lamp-socket construction in which the base of the lamp is interlocked with a slidably mounted inner shell, and for this purpose aims to provide simple means for preventing the inner shell from rotating, and simple means (desirably as part of a reflector or lamp casing associated with the socket) for guiding the inner shell. It also aims to provide a simple insulation-affording mounting for a wire-terminal contact member, aims to provide simple and handsome means for normally concealing the general structure of the socket and particularly the said wire-terminal portion, aims to provide simple means for latching the said concealing means in their normal position, and desirably aims to employ common means for effecting the said latching and for preventing rotation of the inner shell of the socket.

Furthermore, my invention aims to provide a support of a lamp casing or socket (or both) of the above mentioned general types which can readily be attached to the parts supported by it, which will afford the requisite firmness in a two-piece supporting bracket construction suitable for attachment to the fender of a vehicle, and which

will be equally suitable for attachment to a more nearly perpendicular riser when one of the parts of the support is omitted. Still further and also more detailed objects will appear from the following specification and from the accompanying drawings, in which—

Fig. 1 is a side view of a reflector, lamp-socket and supporting bracket combination, showing the same as it appears when attached to the rear fender of a vehicle.

Fig. 2 is an enlarged vertical, central and longitudinal section through the assemblage of Fig. 1, with the lower portion of the supporting bracket omitted.

Fig. 3 is a fragmentary rear elevation of the assemblage of Fig. 1, drawn on the same scale as Fig. 2 but with the ornamental cap of the socket omitted.

Fig. 4 is a transverse section through the socket and cap of Fig. 2, taken along the line 4—4 of that figure with the lamp omitted.

Fig. 5 is a front elevation of the assemblage of Fig. 1, drawn on the same scale as Figs. 2 and 3 but with the lens and the lens-clamping collar omitted.

Fig. 6 is a front elevation of the riser portion of the supporting member, drawn on the same scale as Figs. 3 and 5.

Fig. 7 is a perspective view of the base portion of the supporting member.

Fig. 8 is a perspective view of the outer shell of the socket showing this shell as it appears before it is attached to other elements.

Fig. 9 is a perspective view of the inner shell of the socket.

Fig. 10 is a central, vertical and longitudinal section through the upper portion of the outer shell and the insulating base of the socket, together with the ornamental cap as normally interlocked therewith.

Fig. 11 is a fragmentary section showing the use of certain features of my invention in securing a socket shell to a lamp casing without interposing part of a supporting bracket.

While various novel features of my invention may obviously be employed in a wide variety of connections and for various specific purposes, my invention in general is particularly suited for supporting the tail lamp or the rear stop-signal lamp of an automobile. I am therefore illustrating and describing it in an embodiment designed for

2
this purpose, including as a supporting member a two-piece bracket having a base 1 adapted to be bolted to the rear fender 2 of a vehicle by a pair of bolts 3, this base being 5 secured by a pair of clamping bolts 4 to a riser 5 which is secured to the back of the lamp casing or reflector as hereafter more fully described. To secure the desirable position for the various parts of the supporting member I desirably curve the forked base 1, which base has two arms each equipped with a perforation 6 through which one of the fastening bolts 3 can extend, but leave the similarly forked riser portion 7 10 of the bracket flat, the latter having perforations 8 through which the clamping bolts 4 extend. Then I provide this riser portion with an integral tongue 9 extending upwardly between the two portions 7 as shown in Fig. 7, the tongue 9 having its greater part disposed forwardly of the forward faces of the riser portions 7 by a distance corresponding to the thickness of the riser portion 5 of the base. The latter has 15 a forked lower end affording a pair of wings 10 each of which has a perforation 11 aligning with one of the said perforations 8 when the two parts of the supporting member are assembled, while the intervening bight straddles the lower portion of the tongue.

When the two parts are clamped together as shown in Fig. 1, the rear faces of the wings 10 bear flatwise against the riser portion 7 of the bracket base, while the portion 20 of the riser connecting these wings bears forwardly against the rear of the tongue 9. Thus arranged, the tongue 9 cooperates with the riser portion 7 in holding the riser securely against any forward or backward 25 swinging movement. The riser 5 is desirably stiffened by having a longitudinal groove 11 formed therein as shown in Figs. 2 and 6, and has at its upper end a forwardly concaved ring formation 12 which is curved to fit snugly against the back of the casing 13, this back being here shown as also forming the reflector of the lamp. The ring 12 has a bore of such size as to fit slidably over 30 forwardly projecting fingers 17 on the outer shell 14 of the lamp socket, and this outer shell has its main cylindrical portion spaced from the said fingers by an outwardly directed flange 15 formed by first expanding the shell diametrically and then collapsing 35 the expanded portion upon itself to afford an annular shoulder against which the rear face of the ring 12 bears when the parts of the lamp are assembled. The reflector or lamp casing 13 has a series of secondary 40 perforations or slits 16 through which the fingers 17 respectively extend forwardly of the lamp, each of the fingers 17 being bent back tightly against the forward surface of the reflector 13 so as to clamp the reflector 45 and the ring-shaped upper end of the bracket

against the collar 15 on the outer shell 14 of the socket.

The outer socket shell 14 also has rearwardly directed fingers 18 which are turned inwardly behind the insulating base 19 of the socket, the latter being desirably in the form of a disk of hard rubber having a central perforation through which a tubular contact member 20 extends. This contact member is headed over against both faces of the insulating disk and is threaded to receive a binding screw 21 by means of which the tip of a wire 22 can be clamped against the contact member, so that the latter forms both a wire terminal and a contact element 90 adapted to engage one terminal of the lamp.

Slidably mounted within the outer socket shell is an inner shell having a cylindrical portion 23 which slidably fits the central bore of the reflector and which is equipped with oppositely disposed cam slots 24 arranged for interlocking with the usual projecting pins 25 on the base 26 of an incandescent lamp, each of the cam slots being bayonet slots having inclined connections 95 between their entrance portions 46 and their notched locking portions 27 as shown in Fig. 9. The inner socket shell also has at its rear end an outwardly directed flange 28 which slidably fits the bore of the main portion 14 of the outer shell, and this flange 28 has peripheral notches 29 each of which engages a longitudinal indentation 50 on the said portion 14 of the outer socket shell so as to prevent the inner shell from rotating with respect to the outer shell. Interposed between the flange 28 and the inner portion 30 of the reflector or lamp casing (or the portion of the reflector between the central bore thereof and the slots 16) is a compression spring 31 which continuously urges the inner shell rearwardly or towards the insulating base 19 of the socket, thereby tending to force the contact terminal 32 on the end of the lamp base into engagement with the contact member 20 mounted on the insulating base of the socket. When a lamp is being inserted, the rotation of the lamp while moving its projecting pins 25 from the entrance portions 46 of the cam slots to the locking notches 27 of these slots draws the inner shell forwardly of the socket against the resistance of the spring, and when the projections have reached the locking notches the pressure of the spring holds the lamp firmly latched and also holds the contact elements 20 and 32 in proper engagement, it being understood that the other terminal of the circuit is grounded to the metal shell of the lamp base through the metal structure of the lamp after the general manner customary with so called single-pole lamp sockets.

To give the lamp as a whole a finished appearance and to conceal the parts at the

rear of the socket proper, I desirably also employ an ornamental cap 33 having a bore which fits slidably over the main portion 14 of the upper shell and I provide this cap 5 with a number of indentations 34 each of which enters one of the grooves 50 in the outer socket shell. These grooves terminate short of the rear end of the portion 14 of the outer socket shell as shown in Fig. 8, and 10 each of the indentations 34 is so spaced from the collar 15 that this indentation engages the rear end of the adjacent groove 50, thereby preventing the cap from slipping off the socket shell while still permitting its 15 resiliency to allow a detaching of the cap when desired. The cap also has a longitudinal slot 35 as shown in Fig. 2 so as to clear the wire 22. At its forward end the lamp casing or reflector is desirably equipped 20 for supporting a glass lens or lamp front 36, for which purpose I desirably expand the forward end of this lamp casing to an angle-sectioned collar 37 into which the lens is slidably inserted, and desirably employ a 25 resilient clamping ring 38 for holding the lens of the lamp front in this collar, the clamping ring being normally tightened by a screw 39.

With the parts thus arranged, it will be 30 obvious that I am accomplishing the purposes of my invention with an exceedingly simple and cheaply manufactured construction and that by clamping the riser ring 12 and the inner portion of the reflector 13 35 against the collar 15 of the socket by fingers which extend through corresponding slots in the lamp casing or reflector, I secure a firm assemblage without requiring any screws or other auxiliary fastening elements. 40 So also, by having the inner portion 30 of the lamp casing or reflector extend into the bore of the outer socket shell to form an abutment for the spring, I avoid the necessity of providing a separate socket portion 45 for this purpose.

However, while I have thus illustrated various features of my invention in a combination of immediate commercial desirability, and have described the various parts 50 in highly desirable forms, I do not wish to be limited to their combined use as thus disclosed or to the said details of construction and arrangement. Obviously, many variations might be made without departing either 55 from the spirit of my invention or from the appended claims. Neither do I wish to be limited to having all three of the main constituents of my invention used in connection with each other, as the same method of securing a socket shell to a reflector and to an ornamental cap might obviously be employed with other interior socket constructions, or without the inclusion of a riser portion of a supporting member in the connection between the socket shell and the

reflector. For example, Fig. 11 is a fragmentary view showing a lamp casing or reflector as clamped directly against the collar 15 on the socket shell. Neither do I wish to be limited to arrangements in which 70 one and the same member forms the lamp casing and the reflector, although this double function of one part as shown in the illustrated embodiment lends itself to an inexpensive construction. 75

I claim as my invention:—

1. A lamp socket and reflector combination comprising a reflector having in its back a circular perforation and a plurality of slits surrounding and spaced from the said perforation, an outer socket shell provided at its forward end with fingers extending forwardly through the said slits and clinched against the forward face of the reflector, an inner shell equipped with notches for interlocking with the base of the lamp, the said inner shell extending slidably through the said circular perforation in the reflector and having a lateral projection spaced rearwardly from the reflector, coacting means on the two socket shells for preventing relative rotation thereof, and a compression spring disposed between the two socket shells and abutting at its ends respectively against the said lateral projection and against the portion of the reflector between the said circular perforation and the said slits. 90

2. A lamp socket and reflector combination as per claim 1, in which the means for preventing relative rotation of the two socket shells comprise an outwardly concaved grooved portion formed in the outer shell and extending longitudinally of the latter but terminating short of the rear end of the shell and a flange on the inner shell having a notch slidably engaging the said grooved portion, in combination with a cap sleeved upon the outer shell and housing the rear end thereof and having an inwardly directed latching formation entering the said grooved formation. 100

3. A lamp socket and reflector combination comprising a supporting member having a perforation therein, a reflector bearing against the forward face of the supporting member and having a perforation coaxial with the aforesaid perforation but smaller in diameter than the latter and also having relatively small perforations disposed around its said perforation, an outer socket shell having forwardly directed fingers extending respectively through the said small perforations and also having a shoulder formation bearing against the rear face of the supporting member, the said fingers being clinched over the forward face of the reflector to clamp both the reflector and the supporting member against the said shoulder formation; a wire terminal member 115 120 125 130

having a contacting portion disposed with the outer shell adjacent to the rear end thereof but insulated from the said shell, an inner shell slidable within the outer shell and 5 having means thereon for interlocking with the base of a lamp, and a spiral spring disposed in the space between the inner and outer shells and bearing at its ends respectively against a portion of the inner shell 10 and against the radially inward portion of the reflector.

4. A lamp socket and reflector combination as per claim 3, in which the inner shell is slidably guided by the bore of the reflector.

5. A lamp comprising an outer socket shell, a reflector having its back secured to the forward end of the shell and having a portion extending inwardly of the latter, an 20 insulating base secured to the shell and spaced from the said inwardly extending reflector portion, an inner shell slidable within the said outer shell and having cam slots leading from its forward end for receiving lateral projections on the base of a 25

lamp, the inner shell having an outwardly directed formation at its rear end, means preventing relative rotation of the two shells, and a compression spring interposed between the said reflector portion and the 30 said outwardly directed inner shell formation.

6. In combination, a lamp casing having a plurality of perforations disposed in an 35 nular formation, a lamp socket having a shell equipped with fingers extending respectively through the said perforations and clinched against the forward face of the casing, the shell having an enlargement engaging the rear face of the casing and having on its exterior a longitudinal groove 40 terminating forwardly of the rear end of the shell, and a cap sleeved over the shell and abutting against the said enlargement and having a latching projection entering the 45 said groove adjacent to the rear end of the groove.

Signed at Chicago, Illinois, Sept. 13th, 1922.

THOMAS J. KERWIN.
